(57) **CLAIM**

The ornamental design for a mobile telephone, as shown and described.

DESCRIPTION

FIG. 1 is a front left perspective view of a mobile telephone showing my design, depicted in an open position.

FIG. 2 is a top view thereof, depicted in a closed position;

FIG. 3 is a front elevation view thereof, depicted in an open position;

FIG. 4 is a bottom view thereof, depicted in a closed position;

FIG. 5 is a right side elevation view thereof, depicted in an open position;

FIG. 6 is a left side elevation view thereof, depicted in a closed position;

FIG. 7 is a front elevation view thereof, depicted in a closed position; and,

FIG. 8 is a rear elevation view thereof, depicted in a closed position.

The broken lines shown throughout the views that are immediately adjacent to the shaded areas and define unshaded regions, represent the bounds of the claimed design, while any other broken lines are directed to environment and are for illustrative purposes only; the broken lines form no part of the claimed design.
